UNITED STATES PATENT OFFICE.

CHARLES CALVIN TREDWAY, OF LORDSBURG, NEW MEXICO.

FLY-SCREEN.

1,291,267.

Specification of Letters Patent.

Patented Jan. 14, 1919.

Application filed July 13, 1918. Serial No. 244,765.

To all whom it may concern:

Be it known that I, CHARLES CALVIN TREDWAY, a citizen of the United States, and a resident of Lordsburg, in the county of Grant and State of New Mexico, have invented a new and Improved Fly-Screen, of which the following is a description.

My invention relates to screens for doors or windows for excluding flies and other insects while permitting ventilation, and more particularly the invention relates to that type of screen in which outlets are provided to afford egress for the flies, the outlets being of a character to minimize the possibility of flies entering through the outlets.

The general object of my invention is to provide a screen of the indicated character improved in various particulars, whereby certain advantages and results are obtained among which are the following: (1) The means to provide the outlets for the flies is of such a character as to not curtail the ventilating area of the screen, the complete area of the opening presented by the screen frame being preserved. (2) The outlets lead from the top of a darkened chamber so disposed with relation to the screen material that immediately upon a fly reaching the top of the wire mesh he is at the darkened chamber with light only directly ahead to attract him. (3) The darkened chamber is formed at the outer side by a sheet metal strip imperforate except for the fly outlets and at the inner side by the top rail of the screen frame, by reason of which two results follow in that material is economized and the darkened chamber is co-terminous with the wire mesh without curtailing the area of the latter. (4) The upper edge of the metal strip is effectively secured to the top rail of the screen frame by being driven directly into the same.

Reference is to be had to the accompanying drawing in which—

Figure 1 is a front view of a portion of a door screen embodying my invention; and Fig. 2 is a transverse vertical section on the line 2—2, Fig. 1.

In the illustrated example of my invention, 10 represents a portion of a screen door frame having screen material 11. A sheet metal strip 12 is provided at the upper edge of the screen material and secured thereto as by a suitable seam 13. The upper edge 14 of the strip 12 is disposed laterally and

preferably is driven directly into the top rail of the frame 10. The strip 12 forms with the top rail of the frame a darkened chamber 17, the lower portion of the top rail of the frame 10 at the bottom being beveled as at 15 and the lower portion of the strip 12 being oblique to the vertical, and parallel or approximately so with said beveled surface 15. In the strip 12 is stamped up a longitudinal series of tapering outlets 16, the portion of the strip 12 in which the outlets are formed being at the top of the chamber 17, the strip being approximately at right angles to form the front and top walls of said chamber, the rear wall being formed by the beveled surface 15 of the frame 10.

It will be readily understood that by forming outlets 16 directly in the metal strip, labor and material are greatly economized since the complete attachment can be stamped up in a single operation.

The top of the screen material 11 is carried substantially to the plane of the lower edge of the top rail of the frame 10 and therefore the fly upon reaching the top of the screen material is directly at the darkened chamber with light afforded only by the outlets 16 directly ahead of him as an attraction for him to continue his upward trend.

When the fly reaches the darkened chamber, in traveling upward on the screen material, there is a maximum likelihood of his continuing to and through the outlets and it will be seen that the arrangement involves the minimum amount of metal in the strip and at the same time preserves the ventilating area of the screen.

Having thus described my invention, I claim as new, and desire to secure by Letters Patent:

A fly screen of the class described including a frame, screen material affixed thereto, and a sheet metal strip secured at its upper edge to the top rail of the frame and at its lower edge to the upper edge of said screen material, said strip forming with said top rail a darkened chamber in front of said rail, the inner wall of said chamber being formed by the top rail and the front and top walls thereof being formed by said strip, said top wall having outlet openings therein leading directly from said chamber.

CHARLES CALVIN TREDWAY.
